Patented Apr. 4, 1922.

INVENTOR.
Thomas Mahoney

BY

Clement R. Stuckey ATTORNEY.

UNITED STATES PATENT OFFICE.

THOMAS MAHONEY, OF HIGHLAND PARK, MICHIGAN.

TACKING STRIP FOR UPHOLSTERY.

1,411,973.

Specification of Letters Patent.

Patented Apr. 4, 1922.

Application filed April 13, 1921. Serial No. 460,960.

To all whom it may concern:

Be it known that I, THOMAS MAHONEY, a citizen of the United States, residing at Highland Park, in the county of Wayne and State of Michigan, have invented certain new and useful Improvements in Tacking Strips for Upholstery, of which the following is a specification.

In the application of upholstery and body trimming to metallic structures, such as are now common in motor vehicles and the like, it is frequently desirable to provide tacking spots in various places where such become necessary without changing the general design of the structure or adding appreciably to the weight thereof, and at the same time to avoid the use of wooden strips, which are subject to climatic changes and become loose and split.

This invention relates to a tacking strip for use in combination with upholstery body trimming and the like when applied to metal bodies or structures.

The invention consists in the matters hereinafter set forth, and more particularly pointed out in the appended claims.

In the drawings, Fig. 1 is a view of a portion of a motor vehicle provided with tacking strips which embody features of the invention; Fig. 2 is a view in section showing one method of application of the strip; Fig. 3 is a view showing a tacking spot formed in the shell of the body; Fig. 4 is a view in detail of a strip with tacking insert openings; Fig. 5 is a view in section taken on or about line V—V of Fig. 4, showing tacking inserts therein before compression; Fig. 6 is a view in detail of the body of the strip showing the tacking inserts compressed; Fig. 7 is a view in section taken on or about line VII—VII of Fig. 6; Fig. 8 is a view of a tacking tab applied to a spring.

Referring to the drawings, a strip 1 is formed of bendable metal that is provided with apertures 2 which may be of any desired form, circular, rectangular or polygonal. An insert of wood fibre 4 which originally conforms in dimension to the aper-

ture in which it is placed and with the grain thereof transverse to the plane of the strip, is inserted in the aperture and is then compressed so as to form heads indicated at 5 in Fig. 7, for example, on both sides of the strip 1, which overlie marginal portions 55 of the aperture in which the insert is placed and grip the strip so that the insert is firmly held in position. When in use, the strip may be applied to a tonneau 6 or around wire supports 8 as in Fig. 2. An insert 9 of this character may be inserted directly in the shell of the tonneau at the rim portion which surrounds the seat upholstery; or a piece 10 with an insert 11 may be bent around the upper coil 12 or other portion of a spiral spring and thereby provide means for tacking this tab against any desired support.

One advantage of the construction is the compression of the fibre or wood insert 70 which thereby holds a tack or the like with greater firmness than is possible in non-compressed wood, while at the same time the expanding of the end portions of the insert, prevents the latter from working out of the strip in which it is contained.

Obviously changes in the detail of construction may be made, and I do not care to limit myself to any particular form or arrangement of parts.

I claim as my invention:

1. A tacking strip comprising a bendable metal band provided with apertures and fibre inserts extending through the apertures and having the end portions thereof compressed until they expand over the marginal portions of the aperture.

2. A tacking strip for spring seat constructions comprising a bendable metal band provided with apertures and inserts in the aperture each consisting of a plug of a cross section corresponding to the dimensions of the aperture and having the end portions thereof expanded by endwise compression of the plug to form heads overlying the marginal portions of the aperture.

In testimony whereof I affix my signature.
THOMAS MAHONEY.
